TEXTILE AWNING FABRIC OR SIMILAR ARTICLE

Rupert F. Beckstett, Bay Village, Ohio, assignor to The Astrup Company, Cleveland, Ohio, a corporation of Ohio

Application December 28, 1953, Serial No. 28,241

Term of patent 7 years

(Cl. D92—1)

Fig. 1

To all whom it may concern:

Be it known that I, Rupert F. Beckstett, a citizen of the United States, residing at Bay Village, in the county of Cuyahoga and State of Ohio, have invented a new, original, and ornamental Design for Textile Awning Fabric or Similar Article, of which the following is a specification, reference being had to the accompanying drawing, forming a part hereof.

Fig. 1 is a full scale view of a piece of textile awning fabric, showing my new design; and,

Fig. 2 is an enlarged scale view of the same.

I claim:

The ornamental design for a textile awning fabric or similar article, substantially as shown.
